CLOTH BALE

Hilliard M. Sides, Greenville, S. C.

Application June 2, 1937, Serial No. 145,939

4 Claims. (Cl. 100—14)

This invention relates to a means for packaging bolts of cloth and the like, wherein a plurality of bolts are placed in a superimposed position upon one another and pressure is applied thereto after which a fastening means is secured around the entire assembly. It is necessary to package or bale bolts of cloth in this manner so that a greater number may be shipped as a unit. Heretofore the means for securing the overlapped ends of the straps which were bound around the packages has caused a great difficulty in this particular field. In order to have the most satisfactory ties around the bales, it is desirable that only a short end of the overlapping strap at the fastening point be exposed on the outside of the bale but it is also desirable that a certain amount of slippage be available if for any reason the back pressure should exceed a predetermined amount.

Heretofore it has been necessary to use tools for fastening the two ends together so that they may remain in the proper position relative to the fastener. This practice has, in a large measure, been found unsatisfactory either because of its failure to provide the proper slippage when a predetermined stress has been attained or because it required a complicated expensive fastening means which was difficult to place in an operative position.

It is therefore an object of this invention to provide a fastening means for securing overlapped ends of a tie which is wrapped around a bale of cloth, said means having a slot near one end thereof through which these overlapped ends are adapted to pass and the other end of said fastener being disposed beneath the overlapped portions and held thereagainst by virtue of the back pressure in the bale around which the tie is wrapped. The slot in the fastening means is of such dimensions that when the long end of the fastener is pressed upwardly against the tie by the material in the bale, both of the overlapped portions will be bent by the edges of the slot, thereby creating an added frictional resistance between the overlapped portions. However it should be stated that this added friction is not sufficient to cause one of the ends to break before relative slippage occurs. On the contrary the overlapped end which is disposed near the material will be allowed to slip, whereas the top or outer overlapped portion will remain stationary. This result is caused primarily due to the location of the fastening means.

It is a further object of this invention to provide a fastening means of the class described

which is arc shaped and is adapted to be located near one corner of the bale so that the back pressure in the material will at all times force the long end of the fastener against the lower side of an overlapped end of the strap. By locating the fastener at the corner of the bale the top overlapped end will be held very much tighter by the fastener than the lower overlapped end since there is a greater bend in this end at or about the fastener. This produces a very desirable result because it will enable one to make the outer end very much shorter than the inner end and thereby eliminate a long exposed end which will engage articles with which the bale comes in contact. Of course it will be necessary to make the inner overlapped end extend a substantial distance beyond the fastener so that the slippage can take place without allowing the long end to pass through the slot.

Some of the objects of the invention having been stated other objects will appear as the description proceeds when taken in connection with the accompanying drawings in which:

Figure 1 is an elevation of a bale press showing a plurality of bolts of cloth being pressed into a single bale with my improved fastening means applied thereto;

Figure 2 is a sectional view taken along the line 2—2 in Figure 1, but showing the ends of the bolts of cloth and portions of the press in elevation;

Figure 3 is an isometric view of the bale of cloth shown in Figures 1 and 2 after the pressure has been relieved therefrom;

Figure 4 is an enlarged detail view taken along the line 4—4 in Figure 3 showing the fastening means in the position it occupies relative to the overlapped ends when finally installed;

Figure 5 is a plan view of the fastening means with the overlapped ends of a tie inserted therethrough;

Figure 6 is a sectional view through the fastening means showing the overlapped ends placed therethrough prior to rotating the fastening means to operative position as shown in Figure 4, and

Figure 7 is an inverted isometric view of the fastening means.

Referring more specifically to the drawings the numeral 10 denotes the base of a suitable bale press which has spaced slats 11 placed thereon, thereby providing open spaces or slots 12 therebetween. The base member has upwardly extending posts 13 which support head portion 14 of the press. Slidably mounted in

this head portion is a vertically disposed stem 15, the lower end of which has a press head 16 secured thereto. This press head is raised and lowered relative to the base portion 10 by means 5 of a transverse rod 17 which is rotatably mounted in stem 15 and which has threadably secured around each end thereof collars 18 and 19. These collars have links 20 and 21 secured thereto, said links having their other ends secured to the portion 14. Similar links 22 and 23 are secured to the head portion 16 and to collars 18 and 19. The shaft 17 is rotated by a suitable source of power, not shown, which is connected to sprocket wheel 24 to cause the collars 18 and 19 to be moved away from each other, or toward each other, depending upon the direction of rotation. This movement, will in turn raise or lower the head 16. The parts thus far described are conventional, but it is deemed necessary to show this conventional structure in order to show the preferred method of using my invention.

A plurality of bolts of cloth 27 are stacked upon the slats 11. After the assembly is ready to be 25 baled together the press head 16 is lowered to the position shown in Figures 1 and 2. It will be noted that the press head 16 has slats 28 secured to the lower side thereof which are spaced apart from each other so as to provide slots 29. In the 30 spaces or slots 29 and 12 suitable bale ties 30 are inserted and around the entire assembly. Then the ends of the ties are overlapped and a suitable fastener 31 is used to fasten these ends together at one of the corners of the bale in the manner 35 shown in Figures 2 to 6 inclusive.

The fastener 31 has a slot 32 in one end thereof of whose longer dimension is substantially the same as the width of the ties and whose shortest dimension is considerably greater than the combined thicknesses of the two overlapped ends of the tie. When the desired pressure is applied to the bolts 27 as shown in Figures 1 and 2, the ends of the ties are overlapped as shown in Figure 6 and inserted in the slot 32. Then the long arcuate shaped end 33 of the fastener is rotated in a clockwise manner from the position as shown in Figure 6 until the top side thereof engages the lower side of one of the overlapped ends of the ties. When the pressure is released from the bale 45 the back pressure in all the bolts of cloth will cause the top bolt 27 to press against the lower arcuate surface of the fastener to hold it in the position as shown in Figures 3 and 4.

One explanation as to why the underneath 50 portion of the tie slips under excessive pressure is the rule of fulcrum weight and power. As will be noted in Figure 4, at 32, there are two points of contacts, the lower point being on the lower side of the fastener, with the short end of 55 the tie in direct contact with the fastener. On the other hand, the upper point of contact is on the top or outside of the fastener. Now, note the difference in distance between lower point of contact and tail 33 and the upper point of contact, which 60 and tail 33. Therefore, from a leverage or fulcrum standpoint, the difference in distance between these points of contact and the tail 33 is sufficient to give the lower point of contact a firmer grip than the upper point of contact, which 65 produces the desired results and causes the end of the tie which is disposed along the edges of the bolts and is disposed beneath the other end where they pass through the fastener to do the slipping to relieve excess pressure.

70 Another explanation as to why the long end of

the tie does the slipping, is because that portion which extends across the top of the bale in Figure 3 has frictional contact with the bale which prevents its slipping, while the portion which extends along the vertical side of the bale in Figure 5 3 does not have as much frictional contact with the bale except at its end portion. In any event, actual use, shows that the long end of the tie 30 does the slipping in the fastener to relieve excess 10 back pressure in the bale.

It is very important that this fastener be located at the corner of the bale because the bolts of cloth 27 in the bale will vary in sizes thereby causing the widths to vary. If the fastener 31 should be placed at an intermediate portion on 15 the sides of the bale then it would be necessary to make the ends 33 sufficiently long as to insure that this end would at all times engage the side of a protruding bolt of cloth and be held against the inner side of the tie. Otherwise if a low place 20 in the bale should be encountered by the end of a fastener, the fastener would not be held against the tie and consequently the friction produced between the overlapped ends when they pass through the slot would not be sufficient to hold 25 the two ends together.

It should be further noted that with my improved type of fastener it is not necessary to use tools for inserting the same in position, neither is it necessary to provide collars or other additional means for maintaining it in position. When it has once been installed the outward pressure exerted by the bale will automatically keep the long end of the fastener in a parallel position to the overlapped ends of the tie. Furthermore it is a one piece fastening means with the slot so cut therein that the stress necessary to overcome the friction produced between the overlapped ends will be slightly less than the breaking point of the tie thereby insuring that 40 the long end will slip before the back pressure in the bale breaks the tie.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. A cloth bale comprising a plurality of bolts of cloth stacked one upon the other, a piece of bale tie passed around the bale and having its ends disposed in overlapping relation where the top and one side of the bale meet, a fastener 55 curved to fit the corner of the cloth bale and having a transverse eye through one end thereof which is substantially twice as wide as the thickness of the two overlapped ends of the bale tie, the end of the bale tie which passes along one 60 side of the bale passing through said eye and projecting over a portion of the top of the bale, and the end of the bale tie which passes over the top of the bale passing through said eye on the outside of the other end of the bale tie, the 65 back pressure in the bale serving to press said other end of the bale tie against the inner portion of said overlapping ends to hold the fastener in position to bend the ends of the bale tie where they penetrate said slot, and the gentle curve in 70 the ends of the bale tie permitting slippage of the first-named end when the back pressure exerted by the bale exceeds a predetermined amount.

2. A bale of cloth bolts having a piece of bale tie therearound with its ends disposed in over- 75

lapping relation at one corner of the bale when viewed in cross-section, a curved fastener comprising a member having a transversely disposed slot at one end through which both of said ends 5 are passed in overlapping relation, said fastener also having a tail projecting along the top of the bale and provided with an outer convex surface whereby the back pressure in the bale will press said tail against the lower surface of said bale tie 10 10 and bend the overlapping portions where they pass through said slot, the slot being much wider than the combined thickness of the two ends of the bale tie passed therethrough, thus imparting a gentle curve to the bale tie ends where they 15 15 pass through the slot to allow slippage of the nether end when the back pressure in the bale exceeds a predetermined amount.

3. In combination, a plurality of bolts of cloth which are wider than they are high and are 20 stacked on their flat sides one above the other, a curved fastener disposed at the outer edge of the topmost bale and having a transversely disposed slot through one end and having a tail on its other end, a piece of bale tie adapted to be 25 passed around the bale and to have its ends passed through said slot in overlapping relation and having a longer end and a shorter end, the longer end of said overlapping portion extending along the top of the bale and beneath the other 30 overlapping end, so that the back pressure in the bale will force said tail against the lower surface of the lower overlapping end and will bend the overlapping ends at the point where they pass through said slot, said slot being at 35 least twice as wide as the combined thickness of the overlapping ends of the bale tie to impart a pair of gentle curves to each of said overlapping

ends where they pass through said slot thus allowing the nether overlapping end of the bale tie to slip in said eye when outward pressure of the bale tie exceeds a predetermined amount, said bale tie having an outer convex surface. 5

4. In combination, a plurality of bolts of cloth which are wider than they are high and are stacked on their flat sides one above the other, a fastener curved to fit and disposed at the outer edge of the topmost bale of cloth and having a 10 transversely disposed slot through one end and having a tail on its other end, a bale tie adapted to be passed around the bolts of cloth and having its ends passed through said slot in overlapping relation and having a longer end and a shorter 15 end, said slot being substantially wider than the combined thickness of the two ends of the bale tie which are passed therethrough so that a pair of gentle curves may be produced in the bale tie 20 ends by the back pressure in the bale to allow 25 slippage of the nether end of the bale tie before the breaking point is reached in the bale tie where they pass through said slot, the longer end of said overlapping portions of the bale tie extending along the top of the bale beneath the 30 other overlapping end, so that the back pressure in the bale will force said tail against the lower surface of the lower overlapping end and will gently bend the overlapping ends at the point where they pass through said slot, whereby excessive back pressure will cause the nether overlapping portion to slide relative to the slide and to the other end of the bale tie without any slippage occurring in the outer portion of said bale tie. 35

HILLIARD M. SIDES.
